UNITED STATES PATENT OFFICE.

JAMES RÉNÉ GRABERT AND PHILIP JOHN FRIEDRICH, OF NEW ORLEANS, LOUISIANA,
ASSIGNORS OF ONE-THIRD TO CHARLES CARROLL, OF NEW ORLEANS, LOUISIANA.

MACHINE FOR DEVELOPING MOTION-PICTURE FILMS.

1,197,734.

Specification of Letters Patent. Patented Sept. 12, 1916.

Application filed March 6, 1915. Serial No. 12,599.

To all whom it may concern:

Be it known that we, JAMES RÉNÉ GRABERT and PHILIP JOHN FRIEDRICH, citizens of the United States, residing at New Orleans, in the parish of Orleans and State of Louisiana, have invented certain new and useful Improvements in Machines for Developing Motion-Picture Films, of which the following is a specification.

10 Our invention relates to a film developing apparatus and particularly to an apparatus of this general character which is especially adapted for use in facilitating the developing of continuous films used in motion picture machines.

Heretofore continuous films have been developed by immersing them in a developing fluid contained in a large tank; the films being unwound from their spools in order that 20 the developing fluid might attack every part thereof. In a proceeding of this kind, as may readily be seen, a very large quantity of developing fluid and considerable room is required, as the film is laid or piled in the 25 tank in loops or festoons; and after the film is thus developed, it requires a great deal of trouble and care to rewind it on the spool in a neat and orderly manner. Furthermore, in the process of rewinding the film on the 30 spool, there is always danger of injuring it regardless of the pains taking care and the time involved.

It is the primary object of our invention to provide a film developing apparatus in 35 which the film may be handled in a compact and efficient manner, and subjected to the developing fluid, uniformly from end to end.

Another object of our invention is to so 40 construct the apparatus that only a small amount of the developing fluid will be required to properly develop the film.

Still another object of our invention is to 45 construct the apparatus so that the film, while being immersed in the fluid, will be retained in a neat and orderly manner.

Still another object of our invention is to 50 so construct the apparatus that the film will be caused to traverse the receptacle in a single layer, also in a vertical position.

55 With these and minor objects in view our invention resides in an apparatus embodying the essential features of construction and cooperative relationship pointed out in the subjoined claims, and explained by the illus-

trative embodiment fully set forth in the 55 following description and accompanying drawings; also in certain novel details of construction to be found in said illustrative embodiment, as also pointed out in the claims.

In said drawings:—Figure 1 is a top plan view of the apparatus; Fig. 2 is a side elevation of the receptacle and support; Fig. 3 is a vertical section of the receptacle with the support therein; Fig. 4 is a vertical section 65 of a portion of the support; Fig. 5 is a perspective view of one of the reels showing the end of the film attached thereto; Fig. 6 is a perspective view of a portion of the film attaching means.

Referring to the illustrative embodiment in detail, 1 represents a fluid receptacle and 70 2 a film support having a base 3 substantially the same in horizontal dimension, preferably as the bottom of the fluid receptacle in order to position the support against displacement in the receptacle. Mounted, and spaced apart on the film support 2 are 75 a pair of film reels 4 and 5 either of which is adapted to receive and store a continuous 80 film from an external holder and thereafter deliver it to the other reel as the film is traversed through the fluid within the receptacle.

6 represents a bearing member 85 removably mounted on the film support 2 parallel with the base 3, by means of uprights 7 and attaching screws 8. This bearing member and the base 3 of the film support provide journal bearings for the film reels 4 and 5. 90 Supported on the member 6 is a bearing bar 9 which may have an intermediate raised portion 10 providing a handle for the film support; and this bar 9, together with the member 6 provides journal bearings for the 95 reel-driving gears at the respective ends, each gear comprising pinions 11 and 12, one of which, namely 11 is mounted coaxially with the film reel and constructed to mesh with the pinion 12, whose arbor is adapted 100 to receive and be rotated by a suitable crank 13.

The film reels 4 and 5 are provided with clips for attaching the film thereto. Each clip comprises a plate 14 rounded to conform with the reel and constructed with notched pins 15 which are adapted to pierce the film and engage suitable openings 16 in

the reel. These openings 16 have decreased portions 17 engaging with the pin notches, by an endwise movement of the plate, thereby providing slot and pin connections for 5 preventing the accidental removal of the attaching clips.

The operation of the device is as follows: Either reel 4 or 5 may be removed and placed in any other winding apparatus, but 10 preferably a portion of the film is drawn from an external holder and attached to one of the film reels (for instance reel 5, Figs. 1 and 2), by means of the attaching clip; then the crank 13 is rotated, thereby 15 winding the film on the reel, after which the loose end of the film thus wound is attached to the reel 4 in the same manner. The crank is then transferred to the axle of the pinion 12, which drives the reel 4. With the film 20 thus attached, the support is placed in the fluid receptacle and sufficient fluid poured therein to immerse the film, the fluid level being preferably at the frame member 6. The crank is then rotated and the film 25 caused to traverse the fluid in the receptacle, in a vertical plane, by winding the film from one reel to the other; the film may be passed through the developing fluid as many 30 times as desired, or the developing, fixing and washing fluids successively if a plurality of fluids are successively introduced into the receptacle, it being merely necessary to shift the crank from one pinion 12 to the other as the film is to be wound back and 35 forth. With the film thus developed, the support is removed from the fluid receptacle and the film wound upon one of the reels 4 or 5. To remove the film from the support, the thumb screws 8 are taken out and the 40 parallel member 6 removed, after which the wound film and reel may be transferred bodily for winding off on the drying frame or other desired manipulation.

From the above description it may be 45 seen that a roll of continuous picture film may be developed with uniformity, and very conveniently without danger of injury, and without the use of a large tank on a large quantity of developing fluid.

50 We claim:—

1. In a film developer, embodying in its structure, a fluid receptacle, the combination of a support, a film storing and traversing means provided on said support 55 adapted to receive and store the film from an external holder and traverse it within the receptacle, said film storing and traversing means comprising a pair of reels spaced apart on the support, and said support comprising upper and lower members between which said reels are journaled in vertical position whereby the film in traversing the developing fluid is held in a vertical plane.

2. In a film developer, the combination 60 of a fluid receptacle, a support independent

of but adapted to be applied to the fluid receptacle, and film storing and traversing means provided on said support adapted to receive and store the film from an external holder and traverse it within the receptacle; 70 said film storing and traversing means comprising a pair of reels spaced apart on the support, and said support comprising upper and lower members between which said reels are journaled in vertical position, whereby 75 the film, in traversing the developing fluid is held in a vertical plane.

3. In a film developer, the combination of a fluid receptacle, a support independent of but adapted to be applied to the fluid 80 receptacle, and film storing and traversing means provided on said support adapted to receive and store the film from an external holder and traverse it within the receptacle; said film storing and traversing means comprising a pair of reels spaced apart on the support, and said support comprising three parallel members, the intermediate lower member providing journal bearings for said 85 reels and the intermediate and upper member providing journal bearings for a reel driving means.

4. In a film developer, the combination of a fluid receptacle, a support independent of but adapted to be applied to the fluid receptacle, and film storing and traversing means provided on said support adapted to receive and store the film from an external holder and traverse it within the receptacle; 90 said film storing and traversing means comprising a pair of reels spaced apart on the support, and said support comprising three parallel members, the intermediate lower member providing journal bearings for said reels and the intermediate and upper members providing journal bearings for a reel driving means; and said reel driving means comprising a pair of toothed pinions.

5. In a film developer, the combination of a fluid receptacle, a support independent of but adapted to be applied to the fluid receptacle, and film storing and traversing means provided on said support adapted to receive and store the film from an external holder and traverse it within the receptacle; 100 said film storing and traversing means comprising a pair of reels spaced apart on the support, and said support comprising three parallel members, the intermediate lower member providing journal bearings for said 105 reels and the intermediate and upper members providing journal bearings for a reel driving means; and said reel driving means comprising a pair of toothed pinions.

6. In a film developer, the combination of a fluid receptacle, a support independent of but adapted to be applied to the fluid receptacle and film storing and traversing means provided on said support adapted to receive and store the film from an external 110

holder and traverse it within the receptacle; said film storing and traversing means comprising a pair of reels spaced apart on the support, and said support comprising three parallel members, the intermediate and upper members being removable from the lower member.

The foregoing specification signed at New

Orleans, Louisiana, this 18th day of February, 1915.
